1 Claim. (Cl. 240—128)

This invention relates to releasable retaining means, in particular, for the bowl of an electric lamp which has retaining members arranged on a support to grip the rim of the lamp bowl from below, in the working position. Such lamps are known as "all-glass" lamps.

In known arrangements of this kind, the retaining members are actuated by a lever, which projects radially over the rim of the lamp bowl. These very advantageous devices are considered unacceptable in many cases for aesthetic reasons, owing to the laterally projecting and thus visible actuating lever.

It has already been proposed to associate a rocking-lever spring assembly with the retaining members so that, on putting the bowl in place, one arm of a two-armed angled lever is pivoted, thereby the other arm of this lever is swung into the working position, gripping the rim of the bowl from below. Since the spring-loaded angled lever snaps into position, thus striking the bowl rim, the bowl is often damaged and, consequently, can only be made of glass having a certain minimum thickness.

It is an object of the present invention to provide improved releasable retaining means particularly for electric all-glass lamp bowls.

According to the present invention we provide releasable retaining means for the bowl of an electric all-glass lamp or the like which have retaining members mounted on a support and arranged to grip the bowl rim from below in the position of use, in which said retaining members comprise parts which are mounted on the support and are radially displaceable against the action of springs. Said parts are displaced inwardly when the bowl is put into position. Once the bowl reaches its position of use, they return into their initial position under spring action and grip the bowl rim from below. A reverse process takes place when the bowl is removed.

Suitably, said parts comprise rollers each being displaceable inwardly against the action of a return spring.

The proposal of the invention is realized advantageously in such a manner that, on mounting and on removing the bowl, each of the rollers is radially displaceable in a recess of the base plate of the support and of the cylindrical rim of the support, and has a bearing pin guided in a groove of the base plate.

The return spring may comprise a spring bearing against the circumference of the roller bodies.

It is advisable to construct the roller bodies so that their peripheries have a high coefficient of friction, either by peripherally roughening them or by lining them with a material having a high coefficient of friction, e.g. rubber.

In an alternative construction according to the invention, an arched portion of a spring projects outwards through an aperture of the support rim and replaces said rollers. One end of said spring is fast with the base plate of the support, while the other end is radially displaceable in a guiding groove of said base plate.

The resulting advantage is that only a single component combining a projecting part and a return spring is required. The bearing pins and guiding grooves

2

mentioned above can also be dispensed with. To this must be added the advantage that, since the retaining member comprises the spring itself, the latter is in continuous resilient contact with the bowl when the latter is mounted or removed, so that a danger of damage to the bowl by a snapping movement of the retaining member is virtually avoided.

The concept of this invention may be developed further, based on the observation that it is necessary not only to maintain securely the bowl in its position of use and to render possible its mounting and removal without danger of breakage, but that it is also particularly important to hold said bowl immovable in its position of use despite dimensional deviations which are unavoidable in the manufacture of such bowls.

Accordingly, the present further development provides that the arched portion of a blade spring projecting outwards through an aperture in the rim of the disc-shaped support acts on the bowl in the radial and axial directions relative to the support. Thus, this arched spring portion is so constructed and arranged that one end of the spring is anchored to the bottom of the support, while the other end of the spring extends freely upwards.

A spring of this kind, which acts as retaining member and is also active as a spring element, has an action component in the radial direction of the support and also an action component in perpendicular to that direction, i.e. in the axial direction of the support. It is thus ensured that manufacturing tolerances are compensated and that the bowl is maintained in its position of use not only reliably but also without rattling. A further advantage is that the element here considered is inexpensive to manufacture, e.g. by stamping or pressing, and is also simple to mount. It is also advantageous that the retaining member does not require to be first moved into an initial or preparatory position, as is the case with rocking-lever assemblies, prior to mounting the bowl. This is important because, in this manner, even technically unskilled housewives can mount and remove the bowl without error and difficulty.

In order to prevent the free upper end of the blade spring from rubbing against the wall or ceiling of the room, the support may be provided with a protective means against which the free end of the spring slidably bears.

It is of course possible to combine several retaining members of the aforescribed type into a single unit. The latter then must be provided with a central hole for the screw serving to fasten the lamp to the ceiling, wall, or the like, or eccentric fastening screws must be employed.

Another development of the invention is that a rod spring is employed as return spring; the one end of the rod spring is fastened to the support and the spring extends perpendicularly to the direction of movement of the roller to act on the latter with its free end.

In an advantageous construction, according to the invention the rod spring extends through the roller and serves simultaneously as its bearing pin and this dispenses with separate bearing means for the rollers.

According to a further feature of the invention, two rod springs of two diametrically opposite rollers can be formed integrally and as an approximately semicircular arch spring.

Embodiments of the invention will now be described, by way of example, with reference to the accompanying drawings in which:

FIG. 1 is a section through an all-glass electric lamp having releasable retaining means for the lamp bowl;

FIG. 2 is a top view of the lamp but with the bowl removed;

FIG. 3 is a fragmentary section showing another construction;

FIG. 4 is a fragmentary section showing a further construction;

FIG. 5 is a section on the line V—V of FIG. 4;

FIG. 6 is a section showing another lamp construction;

FIG. 7 is a top view corresponding to FIG. 6 but with the bowl removed;

FIG. 8 is a section on the line VIII—VIII of FIG. 6;

FIG. 9 is a section showing a further lamp construction;

FIG. 10 is a top view corresponding to FIG. 9 but with the bowl removed;

FIG. 11 is a section showing a further lamp construction; and,

FIG. 12 is a top view corresponding to FIG. 11 but with the bowl removed.

Referring to FIGS. 1 and 2 of the drawings, support or holder 1, which can be fastened to a wall, ceiling or the like in a conventional manner, comprises a base plate 2, a cylindrical rim 3 and an angled fastening flange 4.

In this embodiment, the base plate 2 has radial apertures 5 for retaining members, said apertures 5 continuing into corresponding apertures 6 of the rim 3. The retaining members, formed as rollers 7, can be displaced radially to and fro in these apertures. To this end, they are mounted with their bearing pins 8 in grooves 9 provided in shackles 10 of the base plate 2. These shackles can be cut out during the forming of the apertures 5 and then angled to the bottom plate.

When bowl 11 is put into position, i.e. is moved against the support from below, the rollers 7 will be pushed inwards through the bowl rim, until they come to occupy the position indicated by broken lines on the right-hand side of FIG. 1. As soon as the bowl has reached its position of use here shown, the rollers 7 return into the initial position under the effect of spring 12, and grip the bowl rim from below.

The drawing shows that this arrangement is substantially simpler in construction than the proposed prior constructions mentioned above, irrespective of whether those with laterally projecting actuating lever or those with a rocking-lever spring assembly are considered. For this reason and also because the device does not engage the bowl rim in a snapping movement, so that the danger of breakage of the bowl is substantially diminished, the new device constitutes a considerable advance in the art.

According to FIGS. 1 and 2, each return spring is a spring arm extending at an angle to the bottom plate and bearing tangentially against the roller body, which is fastened to the base plate at 13 in a suitable manner. However, as FIG. 3 shows, it is also possible to form the spring arm so that it extends from the base plate at an angle and then transforms into a terminal portion extending substantially perpendicularly to said plate bearing tangentially against the circumference of the roller.

According to FIGS. 4 and 5, the spring is U-shaped. One arm bears in the usual manner against the roller, as shown in FIG. 3, while the other arm, extending substantially parallel thereto, is passed through the aperture 5 of the base plate and engages the latter from below with enlarged foot portion 13.

In addition to the advantages already mentioned, the invention also brings the advantage of rattle-free securing of the bowl on the support.

Referring now to FIGS. 6 to 8, the support 1 is fastened to the ceiling, wall or the like of the room, as described above; the support has a base plate 2 and cylindrical rim 3, with fastening flange 4 angled thereto. With its arched portion 17, spring 14 projects outwardly through an aperture 18 of the rim 3. One end 19 of the spring engages the base plate, while its other end 20 can be slid to and fro in slit-like aperture 21 of the bottom plate. The spring end 20 engages the base plate 2 with its enlarged foot portion 22.

As can be seen from the drawing, when bowl 23 is put

in position or is removed, the arched spring portion 17 is pressed radially inwards, while the spring end 20 slides in the aperture 21. As soon as the bowl has reached its position of use, according to FIG. 6, the spring portion 17 returns into its initial position and grips the rim of the bowl from below.

According to FIGS. 9 and 10, the support can again be fastened in the usual manner to the ceiling, wall or the like of the room and comprises bottom plate 2, rim 3 and angled fastening flange 4.

A bent leaf spring (FIG. 9) serves as a retaining member and spring element for holding bowl 23 in its position of use, arched portion 24 of the spring projecting outwards through aperture 25 in the support rim. Spring end 26 is fast with base plate 2 of the support simply by passing it below stamped-out cross-bar 27 and out through aperture 28. The spring can be anchored to the base plate 2 by means of enlarged end portion 29.

The other spring end 30 extends freely upwards and then inwards, and thus the arched portion 24 moves, when the bowl is put into position, both in direction of arrow x and of arrow y. Consequently, the bowl 23 is pressed against the fastening flange 4 in a rattle-free manner; also possible dimensional irregularities are compensated.

Since, when moving the spring 24, the free spring end 30 slides somewhat along the wall, ceiling, etc., and since it is usually very undesirable to chip off plaster particles, etc., during such movement, as such debris falls into the support 1 or into the bowl 23, the support, as shown in the right-hand portion of FIG. 9, may be provided with a sliding protection spar 31. The spar extends flush with the fastening flange 4 being formed during the stamping-out of the aperture 25 and brought into its position of use by upward folding.

As already mentioned, it is possible to combine several retaining members, e.g., the three retaining members of FIG. 10, in a single component.

Lastly, referring to FIGS. 11 and 12, support 1, which is fastened in the usual manner to the ceiling, wall, etc., of the room concerned, again consists of base plate 2, cylindrical rim 3 and angled fastening flange 4. As in the embodiments of FIGS. 1 to 5, rollers 32 serve as retaining members which are radially displaceable in a slot-shaped aperture 33 of the base plate 2. This aperture is continuous with a corresponding aperture 34 in the support rim 3.

The rollers 32 are mounted with their bearing pins 35 in grooves, slits or like apertures 36, provided in two shackles 37 which are cut out during the formation of the apertures 33 and then angled to the base plate 2.

The rollers 32 are under the action of a return spring, which is a rod spring 38, fastened at 39 to the base plate 2 of the support. In the region of the roller, the spring 38 lies substantially perpendicular to the direction of movement of said roller. In this embodiment the spring constitutes the bearing pin (35) of the roller.

When bowl 40 is placed in position, bowl rim 40 displaces the roller 32 from the position shown in full lines to the position indicated by broken lines. As soon as the bowl rim has reached the position of use, as shown in FIG. 11, the rim 40 is moved back by the spring 38 into its initial position. In this position, the roller 32 grips the bowl rim 40 from below and holds the bowl in position.

In order to ensure that the bowl rim 40 is held rattle-free in its position of use against the flange 4, the spring 38 may be pre-stressed in the direction of arrow x, in which case the guiding aperture 36 has an upwardly-directed front extension 41.

For the purpose of introducing the spring 38 into the aperture 36, the shackles are provided with upwardly-opening slit-like apertures 42.

As the drawing shows, the two springs 38 of two diametrically opposite retaining members can be united to form a substantially semi-circular arched spring.

It is of course virtually immaterial what materials have been used in the manufacture of the bowl, which may consist of, e.g., glass, transparent plastic, etc.

The invention can be applied with particular advantages to electric all-glass lamps, but is not restricted to this application. It is also suitable for use with other lamps having covers, and, generally, every where where a ring- or bowl-shaped cover or shade is to be releasably connected with a holder. Consequently, reference will be made in the claims to "electric all-glass lamps or the like." 10

What we claim is:

A releasable mounting for a surface mounted glass bowl having a radially inwardly turned lip and which bowl surrounds an electric light source comprising:

- (1) a plate member;
- (2) means including an annular ring spacing said plate member from and supporting said plate member in parallel relation to the mounting surface;
- (3) means defining a plurality of radial openings through said ring;
- (4) a plurality of spring members formed of flat sheet stock positioned between said plate and the mounting surface and supported on said plate, said spring members each including bowed portions extending radially outwardly of said openings for engagement with the inner undersurface of the turned-in lip of the bowl and urging said bowl into engagement with the mounting surface, said plate member including a plu-

15

20

25

rality of slots adjacent the periphery thereof and in which the ends of said spring members are received within said slots, the extremities of one end of each spring member having an enlarged portion to engage the underside of said plate member whereby when a bowl is pressed over said spring member, the bowed portions are first forced radially inwardly, said end having the enlarged extremity sliding radially inwardly in its slot to permit the bowl to be positioned beyond the bowed portions of said spring member whereupon said bowed portions return to their initial position and urge the bowl into engagement with the mounting surface by engagement with the underside of the inwardly turned lip of the bowl.
